VALVE CAP RETAINER

Charles J. Clarke, Kingsburg, Calif.

Original application March 15, 1935, Serial No. 11,353. Divided and this application July 16, 1936, Serial No. 90,982

1 Claim. (Cl. 138—89.3)

This invention relates to a new and improved valve cap retainer and pertains more specifically to a retainer for use in combination with the ordinary and conventional screw cap found on and used in connection with the ordinary and conventional valve and valve stem of a pneumatic tire inner tube.

The present application constitutes a division of my application Serial No. 11,353, filed March 15, 1935 and entitled "Valve covers and valve cap retainers."

The primary object of the invention is the provision of a valve cap retainer composed of an elastic or similar resilient material.

Another and further object of the invention is the provision of a valve cap retainer adapted to permit quick and ready removal of the valve cap from the inner tube stem to permit access to the uncovered valve to enable the inner tube to be inflated or deflated.

Another and still further object of the invention is the provision of a device having the above specifically enumerated attributes and having the further improved attribute that the retainer prevents the valve cap from being either misplaced or lost when the cap is removed from the valve stem for the purpose of inflating or deflating the tire inner tube.

Other and further specific objects, novel features of construction and improved results and benefits of the present invention will appear in more detail from the following description when read in the light of the accompanying drawing.

35 In the drawing:

Fig. 1 is a view in side elevation of the present improved invention illustrating its application to the valve cap of a conventional inner tube valve stem.

Fig. 2 is a view in side elevation, taken at right angles to Fig. 1, a part of the view broken away and appearing in vertical section and with the valve cap retainer being illustrated in dotted line as it appears when the cap is removed from the stem.

Describing the invention broadly with reference to the accompanying drawing, A designates as an entirety the conventional valve stem of an automobile or similar tire inner tube. The conventional cap which serves as a closure for the upper end of this stem is designated as an entirety at B and the cap retainer and carrier which is also a water and dirt-proof closure, is designated as an entirety at C.

Proceeding now with a detailed description of

the invention and still making reference to the drawing as illustrating the particular improved construction constituting the invention, it will be seen that in conformity with the usual practice the upper end of the valve stem is threaded as indicated at 1, and that the cap B is of conventional form in that it has a lower skirt portion 2, which is internally threaded to receive the upper threaded end portion 1 of the valve stem. Above this skirt portion the cap is enlarged to form a band 3, which is externally roughened and which in conventional use constitutes a finger receiving portion by means of which the cap can be readily rotated for removal from or application to the valve stem. Above 10 this roughened band portion 3, the cap still follows its conventional form in having an elongated portion 4 of reduced diameter having in its upper end a kerf 5, which is adapted to cooperate with the valve (not shown) for tightening it within or removing it from the hollow valve stem A.

An internally threaded nut 6 is adapted to be applied to the upper threaded end portion 1 of the valve stem and by rotation moved downwardly thereon to assume the position clearly illustrated in the drawing, whereby it is considerably below the upper end of the stem and forms a circumferential enlargement at the base of the threaded portion of the stem and also forms a 20 circumferential shoulder 7, the function of which will hereinafter clearly appear.

The cap retainer and closure C is made of rubber or other like and suitable flexible or elastic material and comprises a hollow upper end or head portion 8, which completely embraces and retains under resilient tension the cap skirt portion 2 and roughened band portion 3. The top 9 of the head is provided with an opening to permit passage therethrough of the 30 elongated reduced portion 4 of the cap and extends over and resiliently engages the curved portion 10 of the cap immediately above the cap band 3. Additionally, the head 8 is preferably of a length to extend below the lower end of the 40 cap skirt portion 2 as clearly appears at 11.

In addition to its head portion 8 the cap retainer and closure C comprises a lower ring portion 12, which is carried by and connected to the head portion by two oppositely disposed narrow side wall portions 13 and 14, which provide oppositely disposed windows 15 in the carrier.

The lower ring portion 12 of the retainer is positioned on the valve stem at a point below the nut 6 and has an internal diameter greater than 50 55

the diameter of the valve stem, with the result that it is free to either rotate or reciprocate upon the valve stem, but is of an internal diameter less than the outer diameter of the nut 6 with the further result that the ring in its movement cannot pass upwardly over the nut or by the circumferential shoulder 7 formed by the nut on the valve stem.

The construction of the cap carrying closure 10 C is also such that the side wall members 13 and 14 which unite the ring to the head do not engage or bind upon the stem nut 6, or in any way hinder the free rotation or reciprocation of the ring 12 on the valve stem.

15 From the foregoing description it will be seen that when it is desired to apply an air hose or pump hose to the valve stem to inflate the tire tube, the cap B is removed from the stem in the ordinary and conventional way, viz: by rotation.

20 When the cap retainer and closure has been rotated sufficiently to disengage the cap from the threaded portion of the stem, as illustrated in Fig. 2 of the drawing, the retainer can then be swung or moved against resilient tension of the

25 side walls of the arms 13 and 14 to either side of the valve stem as is illustrated in dotted lines in the before referred to Fig. 2 of the drawing.

Attention is especially directed to the fact that by unscrewing the cap B from the valve stem 1, 30 the lower part of members 13 and 14 and the ring 12 of the rubber closure C are also rotated around the valve stem and the nut 6, since the parts of the closure fit loosely the valve stem and the part 6. By reference to Fig. 2, it will be observed that when the cap B is unscrewed from the 35 part 1 of the valve stem the closure can move vertically until the part 12 engages the member

6. In Fig. 2 the parts are shown in this position, and in said figure the cap B and the part C are shown in dotted lines to be moved to substantially horizontal positions. After the air is supplied or removed through the valve stem A and the hose through which the air is conducted to the inner tube is removed, then the valve and the part C will automatically return to a vertical position when they are permitted. In order to place the valve cap B on the threaded stem 1, it is necessary to depress the valve cap which also depresses the closure until the cap engages the threaded portion 1, at which time the valve cap and the closure can be rotated until the cap has been fully seated on the end of the valve stem 1. By reference to Figure 1, it will be understood that with the parts in the position shown, there is a space between the under edge of the member 6 and the lower edge of the openings or windows 15, and that the part C of the closure has traveled downward sufficiently to enclose the screw threaded portion 1 of the valve stem and make an absolutely dustproof cover for the screw threaded portion of the valve stem 1.

It will also be understood by reference to Fig. 2 of the drawing that with the parts in the positions there shown the upper end of the screw threaded valve stem lies substantially at the upper

edge of the windows 15 and because of this, the part C of the closure carrying the said cap is more readily movable laterally to the position shown in dotted lines in Figure 2. It will be seen, of course, that the side wall or arm portions 13 and 14 are of sufficient length to afford the necessary longitudinal movement of the retainer to permit the rotary removal of the cap B from the valve stem and that when the retainer is swung to either side of the valve stem that the upper end of the stem will extend through one of the windows 15 and be available for the application of an air hose or the like.

With a construction such as described, the cap retainer and closure provides a dust and moisture-proof protection for the valve and constitutes a positive carrier and retainer for the cap to prevent it from being lost or misplaced. While serving the double function of a cap carrier and protecting closure the structure is such that it is in no sense an obstacle to the easy and rapid removal or replacement of the conventional metal valve cap B and is not in the way when it is found necessary to inflate or deflate the inner tube.

Attention is directed to the fact that the present invention can be quickly, readily and cheaply applied to and used in connection with any conventional inner tube by merely applying to the upper end of the tube valve stem the nut 6 or its equivalent. Thus the present invention constitutes a novel and useful appliance which can be cheaply manufactured by reason of its simplicity and which should have a large volume of sale by reason of its highly desirable attributes and numerous prospective purchasers.

I claim:

The combination with a conventional valve stem having an outer threaded end and a conventional internally threaded cap therefor, of a threaded nut on the threaded portion of said valve stem and normally positioned at the lower end thereof and a hollow elastic member having open ends, the outer and upper end portion of said member tightly fitting said valve cap and its inner and lower end loosely surrounding said valve stem at a point below said nut, said hollow member having an elongated elastic intermediate portion interconnecting said upper and lower portions and formed with a window, said intermediate portion loosely fitting said nut and said valve stem, said hollow upper end portion forming a closed wall with said cap which wall extends down to said nut when the cap has been screwed to a closed position on the valve stem thus forming a closure for that part of the threaded portion of the valve stem lying between the inner end of said cap and the outer and upper end of said nut, and the lower portion of the hollow member extending below the nut a distance substantially corresponding to the extension of the upper portion of the hollow member, the parts operating as and for the purpose described.

CHARLES J. CLARKE.
